UNITED STATES PATENT OFFICE.

JOHN F. KELLEY, OF CHICAGO, ILLINOIS.

DRAIN COCK.

Application filed October 16, 1922. Serial No. 594,909.

To all whom it may concern:

Be it known that I, JOHN F. KELLEY, a citizen of the United States of America, and a resident of Chicago, Illinois, county of Cook, have invented a new and useful Improvement in Drain Cocks, of which the following is a specification.

This invention relates to drain cocks for water circulating systems, such as automobile radiators and the like, wherein the drain cock is equipped with means for automatically releasing the water from the system when the atmospheric temperature would otherwise cause the water to freeze.

15 The main objects of this invention are to provide a drain cock having an improved form and arrangement of part for normally closing the liquid passage and which is adapted to automatically open the cock when 20 acted upon by ice formed within the liquid passage; to provide a drain cock having a fragile part arranged to be fractured by the formation of ice within the cock so as to permit the draining of the system; to provide a fragile element of the above character which is readily replaceable; to provide a drain cock of the above character having an improved form of heater arranged for automatic operation upon the opening of the 25 liquid passage so as to melt any ice which may remain in the cock after the outlet has been opened; and to provide improved mechanism for automatically operating a signal when the system is drained.

30 An illustrative embodiment of this invention is shown in the accompanying drawings wherein:—

Figure 1 is a side elevation of a drain cock embodying this invention.

40 Figure 2 is a side elevation of the same, taken from the left of Figure 1.

Figure 3 is a central vertical section taken on the line 3—3 of Figure 2.

Figure 4 is a central vertical section taken 45 on the line 4—4 of Figure 1.

Figure 5 is a diagrammatic view showing the electric circuit, including the heater and signal.

50 Drain cocks embodying the present invention are adapted for use in any liquid circulating system wherein it is desired to drain the system when the atmospheric temperature would otherwise cause the liquid to freeze, resulting in possible serious damage 55 to the pipes. The invention is particularly

adapted for use in connection with automobile radiators.

In the form shown, the drain cock comprises a casing providing a liquid chamber and having an outlet at its lower end, which 60 is normally closed by a fragile element in the form of a replaceable receptacle adapted to be broken by the formation of ice within the receptacle so as to automatically open the cock. In order to prevent the accumulation of ice within the cock after the outlet has been opened, an electric heater is arranged adjacent the liquid passage, and is controlled by a switch, which is automatically operated when the fragile element is 65 broken. The switch also controls a signal which may be either visible or audible for giving notice that the system is drained. Mechanism for operating the switch is arranged within the casing in position to be 70 released for closing the switch when the fragile element is broken.

Referring to the drawings, the drain cock is in the form of a fitting comprising a casing 1, having a liquid passage 2 extending axially therethrough, and having an outlet 3 at its lower end which is normally closed by a replaceable fragile cup-shaped element 4. Mounted on the casing, is an electric heater 5 arranged adjacent the liquid passage 2, and being controlled by a switch 6, which is automatically operated by an improved form of mechanism 7, arranged within the casing. The switch 6 also controls a signal 8.

90 In the form shown the casing 1, comprises a central body part 9, and an enlarged base part 10 provided with a depending peripheral flange 11, which is interiorly threaded to receive a retaining ring 12, for detachably securing the fragile element 4 to the casing. The upper end of the casing is formed to provide a threaded nipple 13 for attachment to the drain pipe, not shown, of the automobile radiator or other water 95 circulating system. The nipple 13 is provided with the usual form of clamping nut 14.

100 Manual control of the liquid passage 2 is provided by means of a plug valve 15, which is seated in a tapered opening 17 extending transversely through the body part 9. Mounted at one end of the valve 15, is a suitable handle 18, whereby the plug valve 105 may be manually turned to bring the central 110

orifice 19 of the valve into and out of register with the liquid passage 2. The valve 15 is normally left open, so as to permit communication between the liquid passage and the fragile element 4.

The cup-shaped fragile element 4 fits within the base part 10, so as to normally close the outlet 3 of the casing, and is provided at its upper end with an annular 10 flange 20, which is held between gaskets 21 and clamped to the base part by the retaining ring 12. The cup-shaped element 4 forms a receptacle for receiving water from the liquid passage 2, and is preferably made 15 of glass so as to be readily broken by the formation of ice within the receptacle to permit the automatic draining of the system.

The heater 5, which is arranged for automatic operation upon the opening of the cock to prevent the accumulation of ice within the liquid passage 2, is in the form of an electric unit, including an arcuate insulated block 22, on which is mounted 20 a resistance element 23 arranged within an arcuate groove 24 formed in one side of the body part 9, adjacent the liquid passage 2.

The heater 5 is connected by conductors 25 to the switch 6, which is mounted on the base part 10 of the casing, and which includes a contact arm 26 mounted at one end of a bell crank lever 27, which is journaled in a bearing 28 formed on the body part 9. The 30 other end of the bell crank 27 is connected to the switch operating mechanism 7, which is arranged for operating the bell crank to close the switch 6 upon the fracture of the fragile element 4.

The switch operating mechanism 7 is in the form of a spring actuated plunger, including a hollow stem 29 slidably mounted in the lower end of the liquid passage 2 and having a head 30, which bears against 45 the base of the fragile element 4. Communication between the liquid passage 2 and fragile receptacle 4 is provided through an orifice 31 formed in the hollow stem 29 adjacent its lower end. The fragile element 4 coacts with the head 30 to hold the plunger in a retracted position against the action of a helical spring 32 embracing the stem 29 and bearing between the base part 10 of the casing and a disc 33 fixed upon 50 the stem 29 by means of a pin 33.1. The disc 33 is connected to the bell crank 27 by a cable 34, which passes through a stuffing box 35 mounted in the base part 10, so that when the plunger is urged downwardly 55 under the action of the spring 32, when the fragile element is broken, the cable 34 causes the bell crank 27 to turn, so as to bring the contact arm 26 into position for closing the switch 6.

In order to permit the free passage of

water into the cup-shaped receptacle 4 from the liquid passage 2, a breather tube 36 extends into the fragile receptacle through a stuffing box 37 mounted in the base part 10. The upper end of the breather tube, 70 which is not shown in the drawings, extends to a point above the normal level of the liquid in the system, as is well understood in the art, and its lower end extends downwardly through the disc 33 of the 75 plunger in sliding engagement therewith.

The signal 8 may be of any desired form. When the drain cock is used on an automobile radiator the signal is preferably in the form of a small incandescent lamp, 80 which may be mounted on the instrument board of the vehicle.

In operation, the plug valve 15 is normally left open so as to permit the water to circulate freely through the hollow stem 29 of the plunger and into the fragile element 4. Due to the exposure of the lower part of the cup-shaped receptacle 4, the water in said receptacle freezes before the 85 temperature of the water in the system falls to the freezing point, with the result that the fragile element 4 is broken by the ice. The fracture of the fragile element 4 opens the cock to drain the system and releases the plunger 7 to operate the heater 5 and signal 8. If it is desired to replenish the 90 system before replacing the fragile element 4, the plug valve 15 is closed.

Although but one specific embodiment of 100 this invention has been herein shown and described, it will be understood that numerous details of the construction shown may be altered or omitted without departing from the spirit of this invention as defined by the following claims.

I claim:

1. A drain cock comprising a casing provided with a liquid chamber having an outlet, a fragile element arranged to normally close said outlet and adapted to be broken by the liquid in said chamber when said liquid expands during freezing, a signal, and operating mechanism for said signal normally held by said fragile element in an inoperative position and arranged for release to operate said signal when said fragile element is broken.

2. A drain cock comprising a casing provided with a liquid chamber having an outlet, a fragile element arranged to normally close said outlet and adapted to be broken by the liquid in said chamber when said liquid expands during freezing, means for detachably securing said fragile element to said casing, a signal, and operating mechanism for said signal normally held by said fragile element in an inoperative position and arranged for release to operate said signal when said fragile element is broken.

3. A drain cock comprising a casing pro-

130

vided with a liquid chamber having an outlet at its lower end, a cup-shaped fragile element forming a receptacle arranged to normally close said outlet and adapted to be broken by liquid in said receptacle when said liquid expands during freezing, a retaining ring arranged to detachably secure said fragile element to said casing, a signal, and operating mechanism for said signal normally held by said fragile element in an inoperative position and arranged for release to operate said signal when said fragile element is broken.

4. A drain cock comprising a casing provided with a liquid chamber having an outlet, a fragile element arranged to normally close said outlet and adapted to be broken by the liquid in said chamber when said liquid expands during freezing, a signal, a spring pressed plunger arranged within said casing and normally held in a retracted position by said fragile element, said plunger being adapted for release when said fragile element is broken, and a connection between said plunger and signal for operating the latter upon the release of said plunger.

5. A drain cock comprising a casing provided with a liquid chamber having an outlet at its lower end, a cup-shaped fragile element forming a receptacle arranged to normally close said outlet and adapted to be broken by liquid in said receptacle when said liquid expands during freezing, a retaining ring arranged to detachably secure said fragile element to said casing, a signal, a spring pressed plunger arranged within said casing and normally held in a retracted position by said fragile element, said plunger being adapted to be released when said fragile element is broken, and a connection between said plunger and signal for operating the latter upon the release of said plunger.

45 6. A drain cock comprising a casing having a liquid passage extending therethrough and having an outlet at its lower end, a cup-shaped fragile element forming a receptacle

arranged to normally close said outlet and adapted to be broken by liquid in said receptacle when said liquid expands during freezing, a spring pressed hollow plunger slidably mounted in said liquid passage and having an opening providing communication between said liquid passage and fragile receptacle, said plunger being normally held by said fragile element in a retracted position and being adapted for release when said fragile element is broken, a signal, and a connection between said plunger and signal for operating the latter upon the release of said plunger.

7. A drain cock comprising a casing provided with a liquid chamber having an outlet, means arranged to normally close said outlet and adapted to be acted upon by the liquid in said chamber for opening said outlet when said liquid expands during freezing, an electric heater arranged adjacent said liquid chamber, a switch controlling said heater, and operating mechanism for said switch normally held in an inoperative position and coating with said means so as to close said switch when said outlet is open.

8. A drain cock comprising a casing provided with a liquid chamber having an outlet at its lower end, a cup-shaped fragile element forming a receptacle arranged to normally close said outlet and adapted to be broken by liquid in said receptacle when said liquid expands during freezing, an electric heating unit arranged on said casing adjacent said liquid chamber, a switch mounted on said casing for controlling said heating unit, a spring pressed plunger arranged within said casing and normally held in a retracted position by said fragile element, said plunger being adapted to be released when said fragile element is broken, and a connection between said plunger and switch for closing the latter upon the release of said plunger.

Signed at Chicago this 26 day of Sept. 1922.

JOHN F. KELLEY.
